TRAVERSE ROD

James A. Ford, Sturgis, Mich., assignor to Kirsch
Company, Sturgis, Mich., a corporation of Michigan

Filed Dec. 26, 1962, Ser. No. 72,960

Term of patent 14 years

(Cl. D21—1)

FIGURE 1 is a front perspective view of a traverse rod embodying my new design;

FIGURE 2 is a rear perspective view;

FIGURE 3 is a top plan view;

FIGURE 4 is a bottom view; and

FIGURE 5 is an end view thereof.

The traverse rod is shown broken away to indicate indeterminate length.

The broken line showing of a support, drapery hanger and drapery in FIGURE 5 is for illustrative purposes only.

The essential feature of my design resides in the combination in a traverse rod of two planar surfaces meeting

along a lengthwise line and converging frontwardly below a third, narrow surface which is at an angle to the uppermost planar surface, all as shown.

I claim:

The ornamental design for a traverse rod, as shown and described.
